UNITED STATES PATENT OFFICE.

MARCUS H. FORNESS, OF TAYLOR, WISCONSIN, ASSIGNOR TO JOSEPH F. F. WILLETTTE,
OF SEATTLE, WASHINGTON.

TIRE-CHAIN.

1,317,568.

Specification of Letters Patent. Patented Sept. 30, 1919.

Application filed February 21, 1918. Serial No. 218,596.

To all whom it may concern:

Be it known that I, MARCUS H. FORNESS, a citizen of the United States, residing at Taylor, in the county of Jackson and State 5 of Wisconsin, have invented new and useful Improvements in Tire-Chains, of which the following is a specification.

This invention relates to new and useful improvements in tire chains and the principal object is to provide an improved chain which will prevent side-slipping or skidding and spinning of the wheel.

Another object of the invention is to provide a plurality of diagonally arranged 5 chains placed in pairs and having their ends connected with the side members and transversely arranged chains located between the pairs of diagonal chains.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings 5 and specifically pointed out in the appended claim.

In describing my invention in detail, reference will be had to the accompanying drawings wherein like characters denote like 5 or corresponding parts throughout the several views, and in which:—

Figure 1 shows the application of my invention to a portion of a wheel.

Fig. 2 is a plan view of part of my improved chain.

Fig. 3 is a like view of a modification.

In these views 1 indicates the pair of circumferential extending members of the device which are adapted to be placed around 5 the tire and have their ends connected together in any suitable manner. 2 indicates a series of links carried by the side members, the links on one member being opposite the links of the other members as clearly 0 shown in Figs. 2 and 3. I prefer to form these links from one piece of metal bent into loop form and having its ends arranged in parallel relation, said ends being hooked

around a link of the side member. 3 indicates a chain extending in a diagonal manner from a link on one side member to the link of the next pair on the other side member. 4 indicates another chain having one end connected with the other link of the pair and extending at right angles to the chain 3 and having its other end connected with the remaining link of the first pair. These chains are suitably connected together where they cross each other such as one chain being passed through the middle link 55 of the other chain. 5 indicates transverse chains carried by the ends of the diagonal chains. It will be seen that a pair of these transverse chains is located in the space 60 formed by the outwardly extending ends 65 of the diagonal chains. 70

In the construction shown in Fig. 3 a single transverse chain 5' is located in the space between the outwardly extending ends of the diagonal chains 4' and the ends 75 of said transverse chain is connected with the links 2'. In other respects this modification is similar to that above described.

It will thus be seen that the chain is made up of a plurality of pairs of diagonally arranged chains with transverse chains between the ends thereof. In this way a great number of projecting surfaces are 80 formed for preventing the wheels from spinning while the diagonally arranged chains prevent side slipping of the wheel.

The chain is more particularly adapted for use on muddy roads where the ordinary chain formed of transversely arranged links spaced apart will simply pass through the 90 mud without affording a sufficient grip to the wheel to prevent the same from spinning.

It will be apparent from the foregoing that in my novel chain the road-engaging 95 elements to afford traction and to prevent sidewise slipping are arranged so as to rest against the tread portion only of the tire casing. In other words, the road-gripping means is spaced from the side chains. It 100 will also be apparent that in its entirety the chain is absolutely free of elastic or resilient means, being made up of continuous side chains of connected links throughout, road-gripping chains of connected links 105 throughout and loop-shaped links arranged

transversely and interposed between and connecting the side chains and the road-gripping chains.

What I claim is:—

- 5 The herein described tire chain comprising continuous side chains of connected links throughout, loop-shaped links connected at their ends to links of the side chains and extending laterally inward there-
- 10 from and arranged in pairs with the links of each pair in transverse alinement, transverse road-gripping chains disposed between the side chains and spaced apart, and di-

agonal road-gripping chains arranged between, and intersecting each other between 15 the transverse road-gripping chains; said transverse road-gripping chains and diagonal road-gripping chains being each formed throughout of connected links and being connected with the bights of the inwardly extending loop-shaped links on the side chains, whereby said road-gripping chains are separated by intervening spaces from the side chains.

In testimony whereof I affix my signature. 25

MARCUS H. FORNESS.
